(57) **CLAIM**

The ornamental design for a container for dispensable substance, substantially as shown and described.

DESCRIPTION

FIG. 1 is a front, left side, and top perspective view of a container for dispensable substance showing my new design; FIG. 2 is a front elevation view thereof; FIG. 3 is a rear elevation view thereof; FIG. 4 is a left side elevation view thereof; FIG. 5 is a right side elevation view thereof; FIG. 6 is a top view thereof; and, FIG. 7 is a bottom view thereof. The dash-dash-dash broken lines shown in FIGS. 1-7 in the drawings are included for the purpose of showing environmental structure that forms no part of the claimed design. The dot-dash-dot-dash broken lines shown in FIGS. 1-6 in the drawings define the boundary of the claimed design.
